DESIGN FOR A GARMENT HANGER

James F. Fewster, Morrisville, Pa.

Continuation of application Serial No. 75,248,
February 18, 1938, This application April 15,
1938, Serial No. 76,542

Term of patent 7 years

To all whom it may concern:

Be it known that I, James F. Fewster, a citizen of the United States, residing at Morrisville, Bucks County, Pennsylvania, have invented a new, original, and ornamental Design for a Garment Hanger, of which the following is a specification, reference being had to the accompanying drawing, forming a part thereof, in which

Fig. 1 is a front elevational view of a garment hanger showing my new design; and

Fig. 2 is a top plan view thereof.

The dominant feature of the design is shown in full lines. This application is a continuation of my copending application Serial No. D-75,248, filed February 18, 1938.

I claim:

The ornamental design for a garment hanger, substantially as shown and described

JAMES F. FEWSTER.
